E. W. Marshall
ATTORNEY

UNITED STATES PATENT OFFICE.

JOSEPH KENNEDY, OF NEW YORK, N. Y., ASSIGNOR TO THE CLEMENTS COMPANY, OF NEW YORK, N. Y., A CORPORATION OF NEW YORK.

CABLE-HANGER.

1,239,108.

Specification of Letters Patent. Patented Sept. 4, 1917.

Application filed May 8, 1915. Serial No. 26,676.

To all whom it may concern:

Be it known that I, JOSEPH KENNEDY, a citizen of the United States of America, and a resident of New York, county and State of New York, have invented certain new and useful Improvements in Cable-Hangers, of which the following is a specification, reference being had to the accompanying drawings, forming a part thereof.

10 My invention relates to hangers for suspending a cable or the like from a messenger wire or other suitable support, and has special reference to such as are known as cable hangers.

15 One object of my invention is to provide a simple and durable device of this character which may be easily applied to a messenger or supporting wire and which shall very firmly grip the messenger wire so as to avoid 20 torsional or longitudinal movement of the hanger after it is in place.

Other objects and advantages of my invention will be set forth hereinafter and in order that my invention may be thoroughly 25 understood, I will now describe the same in the following specification and then point out the novel features thereof in appended claims.

Referring to the drawings,

30 Figure 1 is a perspective view of a hanger arranged and constructed in accordance with my invention.

A side elevation of the hanger in use is shown in Fig. 2, a messenger wire being 35 shown in section and a cable being indicated by broken lines.

Fig. 3 is a view corresponding to Fig. 2 of the upper portion of the hanger before it is attached to the messenger wire.

40 Fig. 4 is a front view of the hanger in use.

The hooked engaging portions of the hanger are shown on a larger scale in Figs. 5 and 6, the relation of parts while the hanger is being hooked on to the messenger 45 and after it is put in position being shown in respective figures.

In erecting a telephone cable line or the like, the messenger wire is usually strung in position and then a plurality of cable hangers are clamped onto it by a man seated on a swing seat which is suspended from the messenger wire. The hangers are usually spaced about two feet apart and when all the hangers are in position in a span between poles, the cable is threaded through the 50 hangers and pulled from one pole to another sliding along through the loops of the hanger. It is therefore evident that a satisfactory and efficient cable hanger must grip the messenger wire with sufficient firmness 55 to avoid either longitudinal or torsional movement relative to the messenger wire.

It has been my aim to provide a hanger which shall fulfil these conditions and which at the same time can be very readily applied 60 to the messenger wire by the man in the swing seat using one hand and without special tools or implements.

In general, the hanger of my invention comprises a double wire loop which in some 70 respects resembles those of the prior art, but the engaging hooks of my improved hanger are especially constructed to grip the messenger wire in a new way whereby the possibility of either longitudinal or torsional 75 movement relative to the messenger wire is rendered very remote. This depends upon the fact that the hanger comprises a central hook which firmly grips the wire at two approximately diametrically opposite points, 80 as for example, on the two sides of the messenger wire and a pair of spaced hooks one on each side of the central hook, each of which grips the messenger wire on two approximately diametrically opposite sides in 85 quadrature relation to the sides gripped by the intermediate hook, as for example on the top and bottom.

Having special reference to the drawings, the hanger illustrated comprises a pair of 90 loops 10 and 11 which are depended from a common two-part hook 12 at the top and

having its free ends bent to form hooks 13 and 14 located on the respective sides of the two part hook 12.

As clearly shown in the relative large scale views of Figs. 5 and 6, the bend in each part of the double hook 12 shown at 15 is of a smaller radius than that of the messenger 16, with which the hanger is adapted to be used, and the jaws of the hook diverge, 10 forming a wedge-shaped opening to receive the messenger wire. Each of the hooks 13 and 14 is similarly formed but lies in a horizontal instead of a vertical plane, and consequently engages the top and bottom of the 15 messenger wire while the parts of the hook 12 engage the sides of the messenger wire.

Each of the hooks 13 and 14, is furthermore provided with a hump or shoulder 17 on its under jaw to prevent the messenger 20 wire from slipping out of the hook when once it is in place.

Another important feature of my invention is clearly illustrated in Figs. 2 and 3 of which Fig. 3 shows the relation of the hooks 25 12, 13 and 14 before the hanger is mounted on the messenger wire and Fig. 2 shows their relative positions after the hanger is clamped in position. It is evident that the hooks 13 and 14 are pushed downwardly relative to 30 the hook 12 or in other words that the hook 12 is pushed upwardly relative to the hooks 13 and 14. This is further illustrated in Fig. 5 which shows the relative positions of the hooks when the hooks 13 and 14 have 35 been pushed back and the hook 12 has been forced down onto the messenger wire. In order to complete the attaching operation the hooks 13 and 14 must be pushed down 40 until the humps 17 may pass under the wire after which they may be sprung onto the wire with a snap. The resiliency of the 45 spring wire of which the hanger is made will then cause the hooks 13 and 14 to exert an upward pressure upon the messenger wire to force it more tightly into the double hook 12.

The hanger is made of spring wire or other resilient material and it offers a very strong resistance to this displacement and 50 consequently the messenger wire is very strongly forced upwardly by the hooks 13 and 14 into the wedge-shaped opening of the double hook 12.

Detailed modifications may, of course, be effected within the spirit and scope of my invention and I intend that only such limitations be imposed as are indicated in the appended claims:

What I claim is:

1. A hanger comprising a single piece of resilient wire bent to form a two-part central hook having tapered openings between jaws, adapted to engage the sides of a messenger wire, a pair of loops depending from

the parts of the central hook, and end hooks 65 having tapered openings formed in the wire near its respective ends and adapted to engage the messenger wire on the top and bottom.

2. A hanger comprising a single piece of 70 resilient wire bent to form a two-part central hook having tapered openings between jaws, lying in a substantially single longitudinal plane and adapted to engage the sides of a messenger wire, a pair of loops depending from the parts of the central hook and spaced end hooks having tapered openings 75 lying in a substantially transverse plane and humps or projections near the openings of the end hooks on their under 80 jaws, formed in the wire near its respective ends and adapted to engage the messenger wire on the top and bottom, said humps being adapted to hold the wire firmly in the transverse hooks.

3. A hanger comprising a two-part hook having tapered openings between jaws lying substantially in one plane, a pair of loops depending from the parts of said hook, and end hooks having tapered openings lying 90 substantially in a plane at right angles to the first and located one on each side of the two-part hook.

4. A hanger adapted to be affixed to a wire or rod comprising a two-part tapered hook lying substantially in a vertical plane, a pair of loops depending from the parts of the hook, and end hooks lying in a horizontal plane, the horizontal plane of the end hooks being offset relative to the center of 100 a wire or rod as engaged by the two-part hook, whereby said end hooks force the wire or rod into the taper of the two-part hook.

5. A hanger comprising adjacent hooks having tapered openings arranged to act in 105 different directions to each other and to have a supporting wire wedged into said openings; and a loop extending downwardly from said hooks and adapted to support a cable.

6. A hanger comprising a single piece of resilient wire bent to form a downwardly facing hook having a tapered opening arranged to have a supporting wire wedged into said opening, a transverse member 115 adapted to be forced upwardly under said wire and to press the wire into said tapered opening; and a loop extending downwardly from said hook and said transverse member.

7. A hanger comprising a single piece of 120 resilient wire bent to form a downwardly facing hook having a tapered opening arranged to have a supporting wire wedged into said opening, a transverse hook also having a tapered opening and adapted to have the same wire wedged into its opening, the under portion of said transverse hook being arranged to force the wire upwardly 125

into the downwardly facing hook; and a loop extending downwardly from said hooks and adapted to support a cable.

8. A hanger comprising a single piece of 5 resilient wire bent to form a downwardly facing hook having a tapered opening arranged to have a supporting wire wedged into said opening, a transverse hook also having a tapered opening and adapted to

have the same wire wedged into its opening, the under portion of said transverse hook being arranged to force the wire upwardly into the downwardly facing hook and having humps adapted to hold the wire firmly in the transverse hooks.

In witness whereof I have hereunto set my hand this 6th day of May, 1915.

JOSEPH KENNEDY.
